TOP SEALING MACHINE

Charles F. Richard, Battle Creek, Mich., assignor to Johnson Automatic Sealer Co., Ltd., Battle Creek, Mich., a partnership association, limited, of Michigan

Application November 17, 1938, Serial No. 241,076

28 Claims.

(Cl. 93—6)

This invention relates to packaging machinery, and more particularly to means for facilitating and insuring the formation of a tight, dry seal between the top closure elements of a package such as a carton.

One of the objects of the invention is to provide a device of novel construction for receiving cartons from the discharge end of a top sealing mechanism and holding the folded, adhesive coated, top flaps of said cartons in proper position and in pressure contact with one another until the adhesive has thoroughly dried and the flaps have been tightly sealed together.

Another object is to provide a mechanism of improved characteristics which is capable of effecting more rapid and better drying and setting of the top seals of packages, and which requires substantially less floor space, than the belt type driers heretofore used for many years throughout the industry.

A further object is to provide a top seal drying and compression mechanism of the character described which is easily and quickly adjustable to accommodate packages of different sizes, and which constitutes a unitary assembly capable of use in conjunction with package filling and closing machines of various types.

Still another object is to provide a drying and compression unit of novel construction wherein a continuously moving carrier element receives each carton as it leaves the top sealer and holds the top flaps thereof in proper position under both heat and pressure until a tight, dry seal is produced, after which the carton is automatically removed from the carrier and delivered to the output end of the unit.

These and other objects will appear more fully upon consideration of the detailed description of the embodiment of the invention which follows. Although only one particular form of the complete machine, and one modification of the carrier element construction, are shown in the accompanying drawings, it is to be expressly understood that these drawings are for the purpose of illustration only and are not to be construed as defining the scope of the invention, reference being had for this latter purpose to the appended claims.

Referring now to the drawings, wherein like reference characters indicate like parts throughout the several views:

Fig. 1 is a side elevation of one form of top seal drying and compression mechanism embodying the present invention, including a showing of the discharge end of a known type of carton seal-

ing machine and of the mechanism by which the cartons are transferred from the latter to the carrier elements of the former, a number of the carrier elements having been omitted from the drawings in order to better illustrate certain features of the construction; 5

Fig. 2 is a plan view of the mechanism shown in Fig. 1 with the top hold-down plate of the carton transfer mechanism omitted and certain other elements shown in section for clarity; 10

Fig. 3 is an end elevation, on an enlarged scale, of the drying and compression mechanism shown in Figs. 1 and 2 with certain of the elements shown in section along the line 3—3 of Fig. 2; 15

Fig. 4 is a sectional view in elevation taken substantially along line 4—4 of Fig. 5, but omitting the carrier elements and certain other members so as to more clearly illustrate the frame construction and the means by which the mechanism is adjusted for use with cartons of different 20 heights;

Fig. 5 is a plan view, with certain parts shown in section substantially along the line 5—5 in Fig. 3, of the end of the mechanism shown in Fig. 3, including a showing of the means by which the cartons are removed from the carrier elements and delivered from the machine; 25

Fig. 6 is a side view of the carton removing mechanism taken substantially on line 6—6 of Fig. 3; 30

Fig. 7 is an exploded view of one of the carrier elements of the mechanism shown in Figs. 1—6 illustrating the manner in which the various component parts of said element cooperate with one another; 35

Figs. 8 and 9 are elevation and plan views, respectively, of the carrier element of Fig. 7;

Fig. 10 is a sectional view of the carrier element taken substantially on line 10—10 of Fig. 8, but showing the heating and compression member in elevated position; 40

Fig. 11 is an enlarged elevation view of a modified form of carrier element including side compression members for insuring that the small inner flaps of the carton remain in contact with the larger outer flaps during the compression and drying of the top seal; 45

Fig. 12 is a fragmentary end elevation, on an enlarged scale and partially in section, of the mechanism of Figs. 1—6 as modified to embody 50 carrier elements of the construction shown in Fig. 11, this view corresponding in scope to the upper left-hand portion of Fig. 3;

Fig. 13 is a fragmentary plan view of the modified carrier element of Figs. 11 and 12, with cer- 55

tain parts omitted and others shown in section, illustrating the operation of the side compression members as the carrier element passes the carton receiving station; and

- 5 5 Figs. 14 and 15 are diagrammatic plan and vertical sectional views showing (in an exaggerated manner) the way in which the side compression members of Figs. 11-13 operate upon a carton to prevent depression of the small inner flaps during 10 the drying and compression of the top seal.
- The mechanism of the present invention comprises primarily a plurality of carrier or pocket elements continuously movable in a horizontal plane each adapted to carry a filled and closed 15 carton and to apply heat and pressure to the adhesive coated top flaps thereof to insure the making of a tight, dry seal, means for transferring the cartons from the discharge end of a top sealing machine to the carrier elements, and 20 means for automatically removing the cartons from said elements after the drying and setting of the top seals. Each of the carriers includes a compression plate which is automatically lowered and raised into and out of pressure contact with 25 the top flaps of the carton and which is provided with an electrical heating element energized through travelling brushes from stationary bus bars supported on the frame of the machine. The entire mechanism is so constructed that it 30 may be readily adjusted to accommodate cartons of various sizes, this adjustment being effected by a simple manual operation and without in any way dismantling the machine.

Referring now to the embodiment of the invention illustrated in Figs. 1-10, it will be seen that the drying and compression mechanism is supported as a unit on a frame comprising three vertical frame members 20, 21 and 22 substantially A-shaped in end view (Figs. 3 and 4), these 40 members being located one adjacent each end of the unit and the other in the middle and being connected together by horizontal tie members 23 and 24. Secured to the upper ends of frame members 20, 21 and 22 are a pair of longitudinally 45 extending, parallel, channel shaped raceway members 25 and 26, the vertical webs of which extend slightly beyond the end frame members 20 and 22 and serve to properly tie together the upper portion of the framework. Each of race- 50 way members 25 and 26 is provided with a lower horizontal flange 27 having a roller receiving groove or track 28 formed therein, and with an upper horizontal flange 29 also provided with a roller receiving groove or track 30. At the front 55 or carton receiving end of the unit the parallel sections of the raceways formed in the horizontal flanges 27 and 29 of the raceway members 25 and 26 are connected and closed by substantially 60 semicircular lower and upper raceway members 31 and 32, respectively, which are detachably connected to flanges 27 and 29 in any suitable manner. The ends of flanges 27 and 29 at the 65 opposite end of the machine are similarly connected by lower and upper semicircular raceway members 33 and 34, respectively. Inasmuch as these latter members also carry the bearings for one of the sprocket shafts about which passes the carrier or pocket supporting chain next to be described, the connections between raceway 70 members 33 and 34 and flanges 27 and 29 are such that said members may be adjusted longitudinally of the machine when it is desired to take up slack in the chain or otherwise compensate for wear of the various parts.

75 If required for purposes of safety or protection,

the unit may be provided with a suitable cover or enclosure (not shown) which can be removably mounted on the frame members 20, 21 and 22 or the upper horizontal flanges 29 of the raceway members in any desired manner.

The carrier or pocket elements of the mechanism, of which there are any suitable number dependent upon the speed of production desired, are supported and carried by a conveyor chain 35 which passes around and is driven by a sprocket 36 located at the front or carton receiving end of the machine, and which also engages an idler sprocket 37 at the opposite end of the machine. The driving sprocket 36 is fixed to a vertical shaft 38 having its lower end journaled in a bearing 39 mounted in a bracket 40 projecting forwardly from frame member 22, the upper end of said shaft being rotatably supported in bearings 41 and 42 formed as parts of lower and upper semicircular raceway members 31 and 32, respectively. 20 Idler sprocket 37 is fixed to a vertical shaft 43 similarly journaled in bearings 44 and 45 carried by lower and upper semicircular raceway members 33 and 34, respectively.

Secured to the chain 35 at proper intervals 25 therealong are a plurality of carton carrier or pocket elements, the construction of which is shown best in Figs. 7-10. In the embodiment there disclosed, each carrier element comprises a vertically extending supporting block 46 from 30 the rear face of which project a pair of horizontally spaced ears or bosses 47 having threaded into the bottom surfaces thereof the supporting studs of two rollers 48. These rollers are adapted to travel in the groove or track 28 of the lower 35 raceway flanges 27 and lower semicircular raceway members 31 and 33. The upper end of supporting block 46 also carries a rearwardly projecting bracket 49 having a pair of ears or bosses 50 positioned directly above those indicated at 40 47 and receiving in their upper surfaces the supporting studs of a second pair of rollers 51, the latter being adapted to travel in the groove or track 30 of the upper raceway members 29, 32 and 34. By thus mounting the carrier supporting block 46 on four rollers, the carrier is at all 45 times guided in the same path without play.

The connection of each supporting block 46 to the chain 35 is made by means of a single chain pin 52 having its lower end threaded into the upper surface of one of ears 47 and its upper end 50 suitably positioned and held against undesired movement by still another ear or boss 53 projecting rearwardly from supporting block 46 and positioned sufficiently above the cooperating ear 55 47 to permit the reception of the chain 35 therebetween. By thus fastening the supporting block to the chain at only one point, each carrier element follows a true arc in passing around the sprockets 36 and 37 at the ends of the machine. 60

To form a support for the bottom of the carton to be carried thereby, each carrier element is provided with a base plate 54 which is supported in a horizontal position by a bracket 55 extending forwardly from the lower portion of a vertical 65 member 56 slidably associated with supporting block 46. To this end, the front face of block 46 is provided with a vertically extending, undercut groove 57, the groove extending from the bottom of block 46 upwardly throughout the major portion of its height and slidably receiving the base plate carrying member 56.

In order to enable the adjustment of the mechanism to accommodate cartons of different sizes, novel means are provided for raising or 75

lowering the base plates 54 of all of the carrier elements simultaneously and for insuring that said plates remain in the proper position relatively to the rest of the carrier mechanism. In the embodiment illustrated, this adjustability is accomplished by providing the lower end of each vertical slide members 56 with a rearwardly extending stud carrying a roller 58 which extends horizontally into and travels in a groove or track 59 formed in a raceway member 60, said member being of the same configuration as those constituted by the elements 27, 31, 33 and 29, 32, 34 and similarly constructed in so far as the matter of adjustability at the left-hand end (as viewed in Fig. 1) of the machine is concerned. Raceway member 60 is provided with three horizontally extending supporting brackets 61, 62 and 63, these brackets being positioned adjacent and extending into the spaces between the sides of the A-shaped frame members 20, 21 and 22, respectively. The ends of brackets 61, 62 and 63 which project into the adjacent frame members 20, 21 and 22 are provided with vertical, internally threaded bores through which pass adjusting screws 64, the upper ends of the latter being seated in sockets 65 (Fig. 4) while the lower ends are journaled in suitable bearings 66 supported by frame members 20, 21 and 22, each adjusting screw 64 having a collar 67 fixed thereto immediately above the bearing 66. The lower ends of the adjusting screws 64 associated with frame members 20 and 22 have fixed thereto below the bearings 66 sprockets 68 (Fig. 1), while the center screw 64 has a double sprocket 69 similarly located, these sprockets being interconnected by suitable driving chains 70. The lower end of the center adjusting screw 64 is also provided with a bevel gear 71 which meshes with a similar gear 72 fixed to a cross shaft 73 suitably journaled in frame member 21; one end of said shaft extending outwardly beyond the side of said frame member and having fixed thereto an actuating hand wheel 74.

With this construction, it will be evident that a mere actuation of hand wheel 74 is effective, through sprockets 68 and 69 and chains 70, to simultaneously rotate all of adjusting screws 64 in the same direction and thereby raise or lower, depending upon the direction of rotation of the hand wheel 74, the entire raceway member 60. Movement of raceway 60 in turn raises or lowers the base plates 54 of all of the carrier elements simultaneously due to the extension of the rollers 58 into the groove or track 59 of said member. In order to steady the raceway member 60 in its vertical movements and to maintain it in proper position relatively to the other elements of the machine, the horizontal tie members 23 and 24 are provided with a plurality of fixed, vertical guide rods 75 which pass upwardly through suitable bores in guide brackets 76 extending transversely between and interconnecting the parallel sides of raceway member 60.

Returning now to the detailed construction of the carrier elements as shown in Figs. 7-10, there is also provided, in addition to the base plate 54 upon which the bottom of the carton rests, a vertical, forwardly projecting side plate 77 which serves to engage the carton as the carrier passes the loading position and to properly position the carton on the base plate, and a combined heating and compression member, indicated generally at 78, which is adapted

to be lowered into contact with the top of the carton after the latter has been received by the carrier element and to apply both pressure and heat to the adhesive coated top flaps of the carton to produce a tight, dry seal.

In the embodiment illustrated, the combined heating and compression member 78 comprises a supporting plate 79, generally H-shaped in plan as shown in Figs. 7 and 9, two of the legs of the H having downwardly and rearwardly extending arms 80 which embrace the upper end of supporting block 46 therebetween and are pivotally mounted on a fulcrum stud 81 carried by said block. Floatingly suspended from supporting plate 79 is a compression plate 82, 15 rectangular in plan and of substantially the same area as base plate 54, the bottom surface of said compression plate being slightly crowned or pyramidal in form so that, when the plate is moved into contact with the top flaps of the 20 carton, the center portions of the flaps are depressed slightly more than the edge portions to insure a tight seal over the entire area of the carton top. Compression plate 82 is connected to supporting plate 79 by four studs 83 positioned in the corners of the compression plate and passing upwardly freely through holes in the supporting plate, the upper ends of said studs being threaded and carrying nuts 84. In order to permit a yielding movement of the compression plate relatively to the supporting plate, each stud 83 is surrounded by a coil spring 85 interposed between the compression and supporting plates.

The upper surface of compression plate 82 has secured thereto a transversely extending strap 86 which bridges an electrical heating unit 87, said unit being suitably secured to and adapted to heat the compression plate for the purpose of facilitating the drying of the adhesive with which the carton flaps are coated. The upper surface of strap 86 serves as a bearing seat for the rounded head of a central stud 88 which also passes upwardly freely through the transverse web portion of supporting plate 79 and is 45 provided with both a nut 89 on the upper threaded end thereof and a coil spring 90 interposed between the back or upper side of its rounded head and the bottom surface of supporting plate 79. With this construction, the 50 compression plate 82 is capable of practically universal movement about the head of central stud 88 as well as bodily yielding movement relatively to the supporting plate 79, the springs 85 and 90 serving to equalize the pressure exerted 55 by said compression plate on the top flaps of the carton regardless of the position of said plate.

In order to automatically lower and raise the combined heating and compression member 78 for the purpose of bringing the compression plate 82 into and out of contact with the carton flaps, the supporting plate 79 is provided with an upwardly extending arm 91 on the end of which is mounted a cam roller 92. The cam roller 92 is adapted to continuously contact the outer surface of an open cam rail 93 which extends entirely around the machine, said rail being supported in proper position above the path of movement of the carrier elements by a plurality of supporting 70 brackets 94 (Figs. 1-3) which are suitably mounted on top of the upper horizontal flanges 29 of raceway members 25 and 26 and upon the corresponding portions of upper semicircular raceway members 32 and 34. The cam rail 93 is so shaped 75

as to force the combined heating and compression members 78 downwardly to a substantially horizontal position at all times except when the carrier elements are moving through that part of their path which lies between a point slightly in advance of the mechanism which removes the completely dried and sealed cartons from the carriers and a point slightly beyond that at which the freshly closed cartons are received by the carrier elements from the carton sealing machine.

For the purpose of continuously maintaining the cam roller 92 in contact with the cam rail 93, the upper end of arm 91 is provided with a laterally extending stud 95 to which is attached one end of a coil spring 96, the other end of the spring being similarly fixed to a stud 97 projecting laterally from a vertically disposed brush holder support 98 which is suitably secured to the top surface of the upper roller supporting bracket 49 of the carrier assembly. Housed in suitable openings in brush holder support 98 are a pair of brush holders 99 each of which is provided with a carbon brush 100 electrically connected by a flexible wire 101 with the heating unit 81. The brushes 100 are maintained by their holders in continuous electrical contact with a pair of bus bars 102 which are mounted one above the other on fiber supporting plates 103, the latter also being secured to supporting brackets 94 (Fig. 3). It will be understood that the bus bars 102 may be energized in any suitable manner (not shown).

In order to move the carrier elements of the drying and compression unit of the present invention at the proper speed and in the proper timed relation with respect to the operations of the carton sealing machine with which the unit is associated, means may be provided for driving the main shaft 38 of the unit from the carton top sealer itself. In the embodiment illustrated, the lower end of shaft 38 has secured thereto a bevel gear 104 (Figs. 1-3) which meshes with a similar gear 105 fixed to a horizontal, transversely extending shaft 106. One end of shaft 106 is journaled in a bearing 107 carried by a bracket 108 secured to and extending forwardly from one side of frame member 22, while adjacent the other end of said shaft there is a second bearing 109 carried by a bracket 110 extending forwardly from a supporting casting 111 which forms a part of the means for removing the cartons from the carrier elements, later to be described. Fixed to the end of cross shaft 106 adjacent bearing 109 is an adjustable sprocket 112, this sprocket being drivably connected through a suitable chain 113 with a sprocket 114 fixed to a shaft 115 which forms part of the driving mechanism of the carton top sealer machine with which the drying and compression unit is associated. The sprocket 112 is made adjustable in order that the movement of the carrier elements of the drier may be properly synchronized with the operations of the carton sealer machine. The shaft 115 is suitably journaled in bearings carried by the frame 116 of the top sealer, and may obtain its drive in any desired manner from an electric motor (not shown) also mounted on the top sealer frame 116.

In order to insure that the cartons are properly delivered from the exit end of the top sealer to the carrier elements of the drying and compression unit, suitable means are provided for advancing each of the freshly sealed cartons to a position wherein it will be engaged by the side plate 77 of one of the carrier elements as the

latter passes around the forward end of the unit and for guiding the carton during the first part of its travel after engagement by said side plate so as to properly position the same relatively to the base plate 54 and the heating and compression member 78. As illustrated in Figs. 1 and 2, the discharge end of the top sealing machine embodies a known form of belt type discharge conveyor comprising a lower belt 117 and an upper belt 118 driven in unison by suitable chains 10 and sprockets from drive shaft 115 of the top sealer, the belt mechanisms being suitably supported by a framework which includes a bottom supporting member 119, a top supporting member 120 and a pair of vertical side supports 121. Fixed to one of side supports 121 is a horizontal slide bar 122 which extends toward the drying and compression unit parallel to the longitudinal axis thereof and terminates at a point just outside of the path of travel of the carrier elements. Slidably mounted on bar 122 is a slide bracket 123 adapted to be reciprocated along the bar by means of a connecting rod 124 and a suitable operating cam (not shown) which may be actuated in any suitable manner, as by the shaft 115, for example. Slide bracket 123 carries at its left-hand end (as viewed in Figs. 1 and 2) a vertical fulcrum stud 125 on which is pivotally mounted a pusher plate 126. The lower end of fulcrum stud 125 is surrounded by a suitable coil spring 30 127 which is so connected to it and to the pusher plate 126 as to normally urge the latter to a position at right angles to the slide bar 122, but to also permit said plate to rotate about the fulcrum stud 125 in a counterclockwise direction 35 when the slide bracket 123 is moved outwardly away from the drying and compression unit so that the plate may pass by any carton which may then be moving toward the unit between the lower and upper belts 117 and 118 of the discharge conveyor.

As each carton is pushed from between belts 117 and 118 by the pusher plate 126, it passes between a bottom supporting plate 128 which is suitably fixed to the bottom supporting member 119 of the discharge conveyor and a top hold-down plate 129 similarly mounted on top supporting member 120, the top hold-down plate serving to retain the freshly glued and folded top flaps in proper position until the carton comes to rest beneath the combined heating and compression member 78 of one of the carrier elements of the drier and compression unit. As indicated in Figs. 2 and 5, the bottom supporting plate 128 has an arcuate portion extending through substantially 90° overlying the path of travel of the base plates 54 of the carrier elements during the second half of their turn around the forward end of the unit, and is provided with a pair of curved side guide members 130 which are adapted to guide the cartons in the proper curvilinear path from the time when they are first engaged by the side plates 77 until they pass off bottom supporting plate 128 onto the base plates 54. In this connection, it is to be noted that the raceway member 60 of the drying and compression unit is so adjusted by means of the hand wheel 74 that the base plates 54 are positioned at such a height that they pass just beneath the bottom supporting plate 128. The cam rail 93 is also so designed that the compression plates 82 are sufficiently elevated in passing around the forward or carton receiving end of the unit to clear the top hold-down plate 129.

It will be understood that the cam or other 75

means which actuates the connecting rod 124 of slide bracket 123 is so designed and driven at such speed that the pusher plate 126 is reciprocated in proper timed relation to the movements 5 of the carrier elements to insure that cartons are transferred at the proper times from the discharge conveyor of the top sealer to the position in which they are engaged by the side plates 17 of the carrier elements.

10 The mechanism of the present invention is also provided with novel means for automatically removing the cartons from the carrier elements of the drying and compression unit after the top seals thereof have been completely dried and 15 set, which means are manually adjustable simultaneously with the carrier elements to accommodate different sizes of cartons. In the form illustrated, the carton removing mechanism is supported on the hereinbefore identified casting 20 111 in a position off-set from the longitudinal axis of the unit and adjacent the forward or carton receiving end thereof. As previously described, supporting casting 111 is secured to and extends outwardly from frame member 22, and is 25 substantially channel shaped in cross section, as shown in Fig. 6. At its outer end casting 111 is provided with an upwardly extending portion 131, substantially rectangular in plan, in the four corners of which are provided bosses 132 slidably 30 receiving four guide rods 133 to the upper ends of which is secured a base plate 134 which is adapted to support the majority of the elements of the carton removing mechanism.

35 Fixed to base plate 134 is a centrally positioned, downwardly extending boss 135 having an internally threaded bore into which extends the upper end of an adjusting screw shaft 136 journalled adjacent its lower end in a bearing 137 carried by casting 111. The boss 135 of base 40 plate 134 passes freely through a suitable opening formed in the upper surface of portion 131 of casting 111. To the lower end of adjusting screw shaft 136 is fixed a bevel gear 138 which meshes with a similar gear 139 fast to the outer end of 45 a horizontal cross shaft 140 journalled in suitable bearings 141 and 142 carried by casting 111 and frame member 22, respectively. Also fixed to cross shaft 140 adjacent bearing 142 is another bevel gear 143 which meshes with a cor- 50 responding gear 144 secured to the lower end of the adjusting screw 64 associated with frame member 22. With this construction, it will be obvious that, whenever hand wheel 74 is actuated to raise or lower raceway member 60 for the 55 purpose of adjusting the positions of the base plates 54 of the carrier elements, the base plate 134 of the carton removing mechanism is likewise raised or lowered through the actuation of cross shaft 140 and adjusting screw shaft 136.

60 Rotatably supported with respect to the base plate 134 is a circular turntable 145 which is so positioned as to rotate in a plane just beneath that of the base plates 54 of the carrier elements with its periphery underlying a portion of the 65 path of travel of said elements (Figs. 4 and 5). Turntable 145 is provided at its center with a boss 146 which is keyed to a vertical shaft 147 for rotation therewith and axial movement therealong, the lower surface of boss 146 contact- 70 ing the upper surface of the bearing portion of a bracket 148 which is fixed to base plate 134 and in which is journalled the shaft 147. Base plate 134 is also provided with a second bracket 149 secured thereto at a point outside the periphery of the turntable 145 and extending over

the turntable to the center thereof at which point it is provided with a bearing for shaft 147 the bottom surface of which contacts the upper surface of the boss 146. With this construction, raising or lowering the base plate 134 through 5 the means previously described will at the same time slide boss 146 and turntable 145 axially along shaft 147.

The lower end of shaft 147 is journalled in a suitable bearing 150 carried by a bracket 151, 10 substantially U-shaped in plan, which embraces and is secured to the upwardly extending portion 131 of supporting casting 111. Fixed to shaft 147 just above and resting on bearing 150 is a gear 152 which meshes with the gear portion 153 of a 15 combined gear and sprocket member 154 rotatably mounted on a stud 155. The lower surface of gear portion 153 rests on, and the lower end of stud 155 is received in, a boss 156 which is 20 also carried by the bracket 151. The sprocket 20 portion 157 of combined gear and sprocket member 154 is drivably connected by a suitable chain 158 with the upper sprocket of a double sprocket member 159 which is rotatably supported by means of a stud 160 and a boss 161 forming part 25 of a bracket 162, the latter being mounted on the bracket 110 which supports the bearing 109 for shaft 106. The lower sprocket of double 30 sprocket member 159 is in turn drivably connected by a chain 163 with a sprocket 164 fixed 35 to the main driving shaft 38 of the drying and compression unit immediately above the bevel gear 104. With this construction, it will be seen that the shaft 147 and turntable 145 are 40 continuously rotated by driving shaft 38 while the drying and compression unit is in operation, and that the turntable may be adjusted vertically along shaft 147 without interrupting the driving connection therebetween and simultaneously with the adjustment of the base plates 54 of the carrier elements.

In order to properly guide the cartons out of the carrier elements and on to the turntable 145, upper and lower guide members 165 and 166 are provided which, as shown best in Fig. 5, extend 45 angularly inwardly into the path of travel of the cartons as they are carried by the carrier elements. These guide members are so positioned and so shaped that, as each carton comes into contact with the inner ends thereof and continues to travel with the carrier element toward the forward end of the unit (at which time the combined heating and compression member 73 is raised out of engagement with the top flaps by the cam rail 93), the carton is gradually turned 55 on its supporting base plate 54 until one side is parallel to and in contact with the inner surfaces of guide members 165 and 166, and is then slid gradually outwardly over the base plate until it is moved onto the turntable 145. The guide 60 members 165 and 166 may be supported in proper position in any suitable manner, as by a bracket member 167 secured to the underside of base plate 134. For the purpose of guiding the cartons in the proper path as they are carried around 65 on the turntable 145, additional guide members 168 and 169 may be provided, these members being substantially J-shaped in plan and supported in parallel relation to one another above turntable 145 in any suitable manner; as shown, 70 the inner guide member 168 is mounted on studs 170 adjustably threaded into brackets 171 extending outwardly from the end of bearing bracket 149 which supports the upper end of shaft 147, while the outer guide member 169 is similarly 75

mounted on studs 172 carried both by the bracket member 167 and by a Y-shaped bracket member 173 which may be formed integrally with bearing bracket member 148 and thereby secured to base plate 134. The straight ends of guide members 168 and 169 extend outwardly beyond the periphery of the turntable 145 substantially parallel to the longitudinal center line of the drying and compression unit, and are adapted to guide 5 the completely sealed cartons as they leave the turntable and pass to a conveyor or any other suitable mechanism (not shown) by which they may be transferred to the next station in the production line.

10 15 Although the operation of the embodiment of the invention shown in Figs. 1-10 should be clear from the foregoing description thereof, it may be summarized as follows. Filled cartons which have just had their top flaps coated with adhesive 20 and then folded to sealing position on top of one another are successively transferred by the pusher plate 126 from between the belts 117 and 118 of the discharge conveyor of the carton top sealing machine to a position in which they 25 rest on bottom supporting plate 128, with the flaps held down by plate 129, directly in the path of travel of the side plates 77 of the carrier or pocket elements of the drying and compression unit, said elements being continuously moved 30 through the path defined by the raceway members 25, 26, 31, 32, 33, 34 in timed relation with the operation of the top sealer machine and the pusher plate 126. Immediately after each carton has been transferred to the loading position, it 35 is engaged by the side plate 77 of one of the carrier elements and carried around thereby over plate 128, between the guide members 130, until it passes off plate 128 and comes to rest on the base plate 54 of the carrier. At this time, the 40 combined heating and compression member 78 is lowered from the elevated position which it occupies during the time when the carrier element is passing around the forward or carton receiving end of the unit, and, due to the cooperation 45 between cam roller 92 and cam rail 93, is forced downwardly into pressure contact with the top flaps of the carton. As previously described, the compression plate 82 is both yieldably and universally mounted with respect to its 50 supporting plate 79 so that the proper pressure is applied uniformly to the carton top.

The carton is then held in this position in the carrier element while the latter moves the length 55 of the machine, around the rear end thereof, and back to a position closely adjacent the inner ends of the guide members 165 and 166 of the discharge mechanism, during which time the pressure and heat applied by compression plate 82 and heating unit 87 produce a dry, tight seal 60 between the top flaps. As the carrier approaches the discharge position, the combined heating and compression member 78 is again raised out of contact with the top flaps due to the shape of cam rail 93, further movement of the carrier element bringing the carton into contact with the guide members 165 and 166 which thereupon remove the carton from the carrier and transfer it to the turntable 145 in the manner previously 65 described. The turntable 145 then carries the 70 cartons around to the discharge end of the guides 168 and 169, whence they may be transferred in any suitable manner to the next station of the production line.

As hitherto pointed out, both the carrier elements and the carton discharge mechanism of

the drying and compression unit may be simultaneously adjusted to accommodate various sizes of cartons by merely turning hand wheel 74 in the proper direction to raise or lower both raceway member 60, which controls the position of the base plates 54 of the carrier elements, and base plate 134 which controls the position of the turntable 145 and associated elements of the discharge mechanism.

Although the mechanism of Figs. 1-10 is well capable of producing tight, dry top seals on packages of widely varying types, in cases where cartons having small inner flaps are to be sealed and where it is desired to insure that these flaps are held tightly against the large outer flaps when the pressure is applied thereto by the combined heating and compression members, it may be desirable to employ the modified construction of Figs. 11-15.

As shown, each of the modified carrier elements (the construction of which, as well as that of the entire unit, is the same as that illustrated in Figs. 1-10 except for the differences now to be described) is provided with a pressure plate 174 which is fixed to the rear face of side plate 77 and has a horizontally projecting, curved portion 175 extending over the top edge of side plate 77 and inwardly beyond the front face of the latter in a position to engage one of the wider sides of the carton at a point slightly below the top edge thereof. When the carton is properly positioned in the carrier, the portion 175 of pressure plate 174 will push the side of the carton inwardly a slight amount in a plane just below that occupied by the infolded small inner flaps, and will thereby tend to hold said flaps against downward movement when pressure is applied by the compression plate 82 to the outer larger flaps.

In order to balance the pressures exerted on the cartons by plates 174 and to increase the effectiveness of the flap supporting means, a plurality of pressure fingers 176 are provided, one for each of the carrier elements, each having a horizontally projecting, curved portion 177 complementary to and coplanar with the portion 175 of pressure plate 174 and adapted to engage the side of the carton opposite to that against which the portion 175 applies its pressure. While the pressure fingers 176 might be suitably mounted on the carrier elements themselves, the modification of the invention disclosed herein provides for the mounting of these fingers on a separate chain 178 which is driven by a sprocket 179 adjustably secured to the hub of main driving sprocket 36. The sprocket 179 is made adjustable relatively to sprocket 36 in order that the pressure fingers 176 may be moved relatively to pressure plates 174 so as to accommodate cartons of different widths. At the rear end of the machine the pressure finger carrying chain 178 may pass over a suitable idler sprocket (not shown) mounted on idler shaft 43. To insure that the chain 178 travels in the proper path, each of the links 180 by which the pressure fingers 176 are connected to the chain may be provided with a roller 181 which extends upwardly into and moves in a groove or track 182 formed in a horizontally projecting flange 183 carried by raceway members 25 and 26 intermediate the lower and upper horizontal flanges 27 and 29. Should the chain 178 require support against sagging, the raceway members 25 and 26 may also be provided with horizontally projecting bars or rails 184 the outer edges of which extend between the upper and lower side plates of the chain links.

The manner in which the horizontally projecting, curved portions 175 and 177 of a pressure plate 174 and its associated pressure finger 176 operate upon a carton to prevent depression of the small inner flaps during the application of pressure by the compression plate 82 is diagrammatically illustrated in Figs. 14 and 15.

Due to the fact that the pressure fingers 176 are carried on a separate chain and are connected to that chain at positions off-set from the vertical center lines of the carrier elements and from the points of connection of the latter to their carrying chain, the pressure fingers move away from their associated pressure plates 174 when the carrier elements pass around the sprockets at the ends of the unit, the result being that, as indicated in Fig. 13, these pressure members are spread apart sufficiently to permit the free introduction of a carton therebetween when each carrier element passes the loading position. Inasmuch as the removal of the cartons from the carrier elements must also take place while the pressure members are separated, it will be understood that, when using the modified structure of Figs. 11-15, the positions of the inner ends of discharge guide members 165 and 166 are also changed so as to first contact the cartons after the carrier elements have started to move in the curved portion of their path around the front end of the unit. Should it be desired to mount the pressure fingers 176 on the carrier elements themselves, it will be recognized that the same results can be accomplished by pivoting the pressure fingers on the supporting blocks 46 and providing a suitable cam for swinging said fingers outwardly away from the pressure plates 174 during the time when the carrier elements are passing the carton loading and unloading positions.

There is thus provided by the present invention an improved form of mechanism for forming tight, dry seals between the top closure elements of packages which is particularly well adapted for use with high speed, continuous motion carton sealing machinery. With the mechanism herein disclosed, both controlled pressure and heat may be applied to the tops of filled and closed packages while the latter are in motion and for a sufficient length of time to insure thorough drying and setting of the top seals. The construction of the drying and compression mechanism is such that it constitutes a unitary device adapted for use with packaging machinery of various types, and capable of ready adjustment to accommodate packages of different sizes. Because of the improved manner in which the pressure is applied to the package tops, and because of the contemporaneous application of heat to the compression members, a substantially shorter length of time is required to effect drying of the seals than has been necessary with the belt type of drier formerly used, an improved result which is also reflected in a material saving in floor space; for example, with a mechanism of the construction herein disclosed having forty-four carrier elements and a total over-all length of only twelve feet, cartons can be properly sealed at the rate of one hundred twenty per minute, a speed of operation that would require a belt type drier of approximately twenty-four to twenty-eight feet in length. A further advantage of the mechanism of the present invention resides in the fact that the heat and pressure are applied to each package individually by a separate mechanism, thereby fa-

cilitating uniformity of results even though the individual packages may vary in so far as the thickness of the closure elements or the extent of filling of the package is concerned.

While only one complete embodiment of the invention, and one modification of the carrier construction, have been described and illustrated in the accompanying drawings, it will be obvious that the invention is not limited to the exact structures shown but is capable of a variety of mechanical embodiments. For example, the specific manner in which the carrier elements are supported and guided in their movements may be modified without affecting the operation of the mechanism, as may be the particular means illustrated for transmitting power to the various elements of the machine. It is also evident that the number, size and detailed construction of the carrier elements may be varied as desired in order to enable the drying and compression unit to cooperate with top sealer machines of various speeds of operation and to handle packages of various types. It is likewise contemplated that the means by which the various elements of the mechanism are supported in their operative positions may be modified to suit the conditions encountered in different installations. Various other changes, which will now suggest themselves to those skilled in the art, may be made in the form, details of construction and arrangement of the parts without departing from the spirit of the invention. Reference is therefore to be had to the appended claims for a definition of the limits of the invention.

What is claimed is:

1. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for moving said carrier elements in a closed path, means for loading packages into said carrier elements operable in timed relation to the movements of said elements, a member mounted on each of said carrier elements for applying pressure to the top of the package carried thereby, means for moving said members out of and into pressure applying position, said last named means being so constructed and arranged as to maintain each of said members out of pressure applying position during the time when a package is being loaded into the associated carrier element, and means for removing said packages from said carrier elements after the application of pressure thereto.

2. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for moving said carrier elements in a closed path, means for loading packages into said carrier elements operable in timed relation to the movements of said elements, a member mounted on each of said carrier elements for applying pressure to the top of the package carried thereby, means for moving said members out of and into pressure applying position, said last named means being so constructed and arranged as to maintain each of said members out of pressure applying position

- during the time when a package is being loaded into the associated carrier element, means for applying heat to the tops of said packages simultaneously with the application of pressure thereto by said pressure applying members, and means for removing said packages from said carrier elements after the application of pressure and heat thereto.
3. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for continuously moving said carrier elements in a closed path, means for loading packages into said carrier elements operable in timed relation to the movements of said elements, a member mounted on and movable with each of said carrier elements for applying pressure to the top of the package carried thereby, means for raising and lowering said members out of and into pressure applying position, said last named means being so constructed and arranged as to maintain each of said members out of pressure applying position during the time when a package is being loaded into the associated carrier element, and means for removing said packages from said carrier elements after said pressure applying members have been raised out of pressure applying position.
4. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for continuously moving said carrier elements in a closed path, means for loading packages into said carrier elements operable in timed relation to the movements of said elements, a member mounted on and movable with each of said carrier elements for applying pressure to the top of the package carried thereby, means for raising and lowering said members out of and into pressure applying position, said last named means being so constructed and arranged as to maintain each of said members out of pressure applying position during the time when a package is being loaded into the associated carrier element, heating means associated with said pressure applying members for applying heat to the tops of said packages simultaneously with the application of pressure thereto, and means for removing said packages from said carrier elements after the application of pressure and heat thereto.
5. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for moving said carrier elements in a closed path, means for loading packages into said carrier elements operable in timed relation to the movements of said elements, means for applying pressure and heat to the tops of the packages after they have been loaded into said carrier elements, and means for removing the packages from said carrier elements after the application of pressure and heat

thereto including a movable package conveyor member positioned closely adjacent the path of movement of said carrier elements and means for transferring said packages from said elements to said conveyor member.

6. A top seal drying and compression mechanism for use with a packaging machine of the type which delivers to the discharge end thereof packages having closed tops including adhesive coated closure elements folded into contact with one another, comprising a plurality of carrier elements each adapted to receive and support one of said packages, means for moving said carrier elements in a closed path, means for loading packages into said carrier elements operable in timed relation to the movements of said elements, means for applying pressure and heat to the tops of the packages after they have been loaded into said carrier elements, and means for removing the packages from said carrier elements after the application of pressure and heat thereto including a rotatable turntable positioned closely adjacent the path of movement of said carrier elements and guide means extending into the path of movement of said carrier elements for transferring said packages from the latter to said turntable.

7. In a packaging machine, a plurality of carrier elements each adapted to receive and support a package having a closed top including adhesive coated closure members folded into contact with one another, a member mounted on each of said carrier elements for applying pressure to the top of the package carried thereby, means for moving said members into and out of pressure applying position, and means for applying heat to the tops of said packages simultaneously with the application of pressure thereto by said pressure applying members.

8. In a packaging machine, a plurality of carrier elements each adapted to receive and support a package having a closed top including adhesive coated closure members folded into contact with one another, means for moving said carrier elements in a closed path, a member mounted on and movable with each of said carrier elements for applying pressure to the top of the package carried thereby, and means for raising and lowering said members out of and into pressure applying position at predetermined points in the path of movement of said carrier elements.

9. In a packaging machine, a plurality of carrier elements each adapted to receive and support a package having a closed top including adhesive coated closure members folded into contact with one another, means for moving said carrier elements in a closed path, a member mounted on and movable with each of said carrier elements for applying pressure to the top of the package carried thereby, means for raising and lowering said members out of and into pressure applying position at predetermined points in the path of movement of said carrier elements, and means for applying heat to the tops of said packages simultaneously with the application of pressure thereto by said pressure applying members.

10. In a packaging machine, a plurality of carrier elements each adapted to receive and support a package having a closed top including adhesive coated closure members folded into contact with one another, means for moving said carrier elements in a closed path, a member mounted on and movable with each of said car-

- rier elements for applying pressure to the top of the package carried thereby, means for raising and lowering said members out of and into pressure applying position at predetermined 5 points in the path of movement of said carrier elements, and heating elements carried by said pressure applying members for applying heat to the tops of said packages simultaneously with the application of pressure thereto.
- 10 11. In a packaging machine, a plurality of carrier elements each adapted to receive and support a package having a closed top including adhesive coated closure members folded into contact with one another, means for moving said 15 carrier elements in a closed path, a member pivotally mounted on and movable with each of said carrier elements for applying pressure to the top of the package carried thereby, and cam means for moving said members about their pivotal axes 20 out of and into pressure applying position at predetermined points in the path of movement of said carrier elements.
12. In a packaging machine, a plurality of carrier elements each having a member adapted to receive and support a package having a closed top including adhesive coated closure elements folded into contact with one another, means for moving said carrier elements in a closed path, a member mounted on and movable with each of said carrier elements for applying pressure to the top of the package carried thereby, means for raising and lowering said last named members out of and into pressure applying position at predetermined points in the path of movement 30 of said carrier elements, and means for raising or lowering the package supporting members of all of said carrier elements simultaneously to adjust the machine for use with packages of different sizes.
- 40 13. In a packaging machine, a plurality of carrier elements each having a member adapted to receive and support a package having a closed top including adhesive coated closure elements folded into contact with one another, means for moving said carrier elements in a closed path, a member mounted on and movable with each of said carrier elements for applying pressure to the top of the package carried thereby, means for raising and lowering said last named members out of and into pressure applying position at predetermined points in the path of movement of said carrier elements, means for removing the packages from said carrier elements after the application of pressure thereto, and means for 45 raising or lowering the package supporting members of all of said carrier elements and said packaging removing means simultaneously to adjust the machine for use with packages of different sizes.
- 50 14. In a packaging machine, a plurality of carrier elements each having a member adapted to receive and support a package having a closed top including adhesive coated closure elements folded into contact with one another, means for moving said carrier elements in a closed path, a member mounted on and movable with each of said carrier elements for applying pressure to the top of the package carried thereby, means for raising and lowering said last named members out of and into pressure applying position at predetermined points in the path of movement of said carrier elements, means for removing the packages from said carrier elements after the application of pressure thereto, including a ro- 55 tatable turntable positioned closely adjacent the path of movement of said carrier elements and guide means extending into the path of movement of said carrier elements for transferring said packages from the latter to said turntable, and means for raising or lowering the package supporting members of all of said carrier elements and said turntable simultaneously to adjust the machine for use with packages of different sizes.
- 60 15. In a packaging machine, a supporting frame, a conveyor element mounted on said frame for movement thereon in a closed path, a plurality of package carrier elements each having a member connected to said conveyor element and a package supporting member vertically movable relatively to said first named member, and means for raising or lowering the package supporting members of all of said carrier elements simultaneously.
16. In a packaging machine, a supporting frame, a conveyor element mounted on said frame for movement thereon in a closed path, a plurality of package carrier elements each having a member connected to said conveyor element and a second member vertically movable relatively to said first named member, a package supporting member fixed to each of said vertically movable members, a track of the same configuration as the path of movement of said conveyor element, a track follower carried by each of said vertically movable members, and means for raising and lowering said track relatively to said frame to adjust the positions of all of said package supporting members simultaneously.
- 20 17. In a packaging machine, a supporting frame, a conveyor element mounted on said frame for movement thereon in a closed path, a plurality of package carrier elements each having a member connected to said conveyor element and a second member vertically movable relatively to said first named member, a package supporting member fixed to each of said vertically movable members, a track of the same configuration as the path of movement of said conveyor element, a track follower carried by each of said vertically movable members, means for removing packages from said carrier elements including a supporting element, a turntable rotatably mounted on said supporting element in a position closely adjacent the path of movement of said carrier elements and guide means extending into the path of movement of said carrier elements for transferring packages from the latter to said turntable, and common means for raising and lowering both said track and said supporting element relatively to said frame to adjust the positions of all of said package supporting members and said turntable simultaneously.
- 25 18. In a packaging machine of the type including a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate vertically adjustable relatively to said supporting member, and a pressure applying member mounted on said supporting member and adapted for movement relatively thereto into and out of contact with the top of the package supported on said base plate.
- 30 19. In a packaging machine of the type in-

cluding a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate vertically adjustable relatively to said supporting member, a pressure applying member mounted on said supporting member and adapted for movement relatively thereto into and out of contact with the top of the package supported on said base plate, and means for applying heat to the top of said package simultaneously with the application of pressure thereto by said pressure applying member.

20. In a packaging machine of the type including a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate vertically adjustable relatively to said supporting member, a pressure applying member mounted on said supporting member and adapted for movement relatively thereto into and out of contact with the top of the package supported on said base plate, and a heating device carried by said pressure applying member for applying heat to the top of said package simultaneously with the application of pressure thereto.

35. 21. In a packaging machine of the type including a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate vertically adjustable relatively to said supporting member, and a combined pressure and heat applying member pivotally mounted on said supporting member for movement relatively thereto into and out of contact with the top of the package supported on said base plate.

50. 22. In a packaging machine of the type including a plurality of package carrier elements secured to a movable conveyor each adapted to receive and support a package having adhesive coated top closure elements folded into contact with one another to close the package, a package carrier element comprising a supporting block adapted for connection to the conveyor, a member slidably mounted in the lower portion of said supporting block for movement relatively thereto in a vertical plane, a package supporting base plate fixed to said slidable member, and a pressure applying member pivotally mounted adjacent the upper end of said supporting block for movement relatively thereto into and out of contact with the top of the package supported on said base plate.

55. 23. In a packaging machine, a supporting frame, a conveyor element mounted on said frame for movement thereon in a closed path, a plurality of package carrier elements secured to said conveyor element at intervals therealong, each of said carrier elements including a member adapted to support a package having adhesive coated top closure elements folded into contact with one another to close the package and a member movable

into and out of contact with the top of said package for applying sealing pressure thereto, and means associated with each of said carrier elements and movable therewith for applying pressure to opposite sides of the package carried thereby at points slightly below the top edges thereof to prevent depression of the closure elements when sealing pressure is applied thereto by said pressure applying member.

24. In a packaging machine, a supporting frame, an endless conveyor chain mounted on said frame for movement thereon in a closed path, a plurality of package carrier elements secured to said chain at intervals therealong, each of said carrier elements including a member adapted to support a package having adhesive coated top closure elements folded into contact with one another to close the package and a member movable into and out of contact with the top of said package for applying sealing pressure thereto, and a pair of members associated with each of said carrier elements and movable therewith for applying pressure to opposite sides of the package carried thereby at points slightly below the top edges thereof to prevent depression of the closure elements when sealing pressure is applied thereto by said first mentioned pressure applying member, one of each pair of said members being mounted on the associated carrier element and the other being fixed to a second conveyor chain parallel to and movable in synchronism with said first mentioned chain.

25. A packaging machine according to claim 24 wherein the points of connection to their respective chains of each carrier element and the associated chain carried side pressure applying member lie in different vertical planes.

26. A packaging machine according to claim 24 wherein said second conveyor chain is movable relatively to said first mentioned chain to permit adjustment of the horizontal distance between the side pressure applying members of each pair.

27. In a packaging machine of the type including a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate carried by said supporting member, a pressure applying member mounted on said supporting member and adapted for movement relatively thereto into and out of contact with the top of the package supported on said base plate, and means associated with said carrier element for applying pressure to opposite sides of the package at points slightly below the top edges thereof to prevent depression of the closure elements when said pressure applying member is moved into contact therewith.

28. In a packaging machine of the type including a plurality of package carrier elements secured to a movable conveyor each adapted to receive and support a package having adhesive coated top closure elements folded into contact with one another to close the package, a package carrier element comprising a supporting member adapted for connection to the conveyor, a package supporting base plate carried by said supporting member, a pressure applying member mounted on said supporting member and adapted for movement relatively thereto into and out of contact with the top of the package supported on said base plate, a vertical side plate adapted

to contact one side of said package, a horizontal pressure applying member carried by said side plate and having an edge projecting beyond the carton contacting surface of the latter at a height slightly less than that of the top of the package, and a second horizontal pressure applying member coplanar with the first and adapted to apply

pressure to the opposite side of the carton, said second horizontal pressure applying member being so constructed and arranged as to be movable relatively to said first mentioned member to vary the distance therebetween. 5

CHARLES F. RICHARD.
